(57) **CLAIM**

The ornamental design for a wireless receiver, as shown and described.

DESCRIPTION

FIG. 1 is a bottom right perspective view of a wireless receiver;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Elements shown in the drawings in broken or phantom lines form no part of the claimed design, and merely illustrate the environment in which the article embodying the design is used.
